UNITED STATES PATENT OFFICE.

PAUL H. HORWITT, OF SPRINGFIELD, MASSACHUSETTS.

DESIGN FOR PAPER TOWELING OR THE LIKE.

Application filed August 1, 1928. Serial No. 27,653. Term of patent 7 years.

To all whom it may concern:

Be it known that I, PAUL H. HORWITT, a citizen of the United States, residing at Springfield, in the county of Hampden and State of Massachusetts, have invented a new, original, and ornamental Design for Paper Toweling or the like, of which the following is a specification, reference being had to the accompanying drawing, forming a part thereof.

The figure is a view of a piece of paper toweling, or the like embodying my new design.

I claim:

The ornamental design for paper toweling or the like as shown.

PAUL H. HORWITT.
